BOTTLE CRATE

Edward M. Pennock and Lloyd Hale, Minneapolis,
Minn., assignors to G. H. Tennant Company,
Minneapolis, Minn., a corporation of Minne-
sota

Application March 4, 1931, Serial No. 519,918

12 Claims. (Cl. 217—19)

This invention relates to bottle crates, where a series of narrow wooden slats are used to provide the side walls thereof. These slats are superimposed edge to edge and by suitable reinforced metal corner members the crate is formed to provide a strong body portion with side and end walls which have an insulating or cushioning effect in protecting the bottles against shock when the crates strike one against the other and in the handling of these crates when they are stacked one upon the other.

A feature in this crate resides in a simple construction to provide for the manufacture of the same so that the crate may be quickly and easily assembled to form a partitioned crate provided to receive the bottles and hold them in separate compartments. This crate is particularly adapted to milk bottles, however, it may be used wherever it is desired to carry a series of bottles in a crate so that they may be easily removed therefrom.

A feature resides in the partitions which are made up as units and which are slipped or nested between the slats in the assembly of the crate. These partitions are held in place by the edges of the slats and form spacers to divide the inside of the crate into the bottle compartments.

In the drawing,

Figure 1 illustrates a perspective view of a bottle crate having the reinforced corner members and stacking lugs.

Figure 2 is a detail section showing the manner in which the partition unit is held between the slats.

Figure 3 is a perspective view of one of the partition units.

Figure 4 is a perspective view of the bottom unit which is used in making up our crate.

Figure 5 is a perspective view of one of the slats used in making the side walls of our crate.

The crate A may be designed of any suitable shape and nature and the side walls of the same are composed of a series of narrow slats 10 which may be formed of wood or other non-metallic material having a nature to provide a cushion or insulation between the crates so that the bottles held in the crate A will not be broken should the crates be slammed one against the other in use.

The slats 10 have a narrow construction and are formed with longitudinal edge portions 11. In making up the crate A, the slats 10 are formed with a saw-cut or slot 12 near the end thereof so that they may be slipped in between the outer corner member 13 and the inner corner member 14. The outer corner member is formed with inturned edges 15 which engage in the slots 12 of each of the slats 10. This is primarily for the purpose of holding the slats 10 in position in assembly and building up of the side walls of the crate A.

The simplicity of this crate resides in the mak-

ing of the partition units B complete in their entirety, as illustrated in Figure 3 and then placing the same between the edges 11 of the slats 10. A strip 16 formed in a rectangular shape, as illustrated in Figure 3, provides the outer frame 65 of the unit B and by means of the rigid stay-rods 17 and 18 which extend between the sides of the frame 16, we provide suitable spacers which extend at right angles to each other to divide the frame 16 into compartments C for receiving the 70 individual bottles. The stay-rivets 17 and 18 are formed with an annular shoulder 20 which engages on the inside of the frame 16 while the outer end of the rivet or stay-rods 17 and 18 are riveted over to provide the head 1 on the outside 75 of the frame member 16. By riveting these rods 17 and 18 to the strip 16, the frame of the unit B is formed of a rigid strong nature. The rods 17 and 18 extending at right angles to each other touch at their intersecting points. This also 80 tends to make the unit B more rigid and firm so that it may act to provide a partition member when it is spaced between the edges 11 of the side walls of the crate A.

A suitable bottom unit D is formed which is 85 similar to the unit B and which is provided with a strip 22 formed of a rectangular nature like the unit B. In this unit D rivet stay-rods 23 extend in pairs so as to be sufficiently close together to form bottoms for the bottles held in the crate A. 90 The pairs of stay-rods 23 are positioned in relation to the compartments C of the units B so as to come directly under or across the center of these compartments C and thus the bottom of the bottle will rest upon these rods 23. In this manner, the unit D forms a bottom member while the unit B forms a partition member for the 95 crate A.

In assembling the crate A, the simplicity of the structure accomplishes a result to provide an 100 economical bottle crate A which may be used to carry milk bottles or any other kind of bottles and which has a rigid and strong structure to withstand hard use. The lower slats 10' of the crate A may be made narrow so that the bottom unit D 105 may be placed closer to the lower edge and in assembling the crate A, the lower slats 10' are slid into engagement with the angle sides 13 and 14 and then the bottom unit D is dropped into place, then the next side slats 10 are dropped into 110 engagement with the top of the bottom unit D in the same manner as the unit B is held and illustrated in Figure 2, so that the edges 11 of the adjacent slats engage with the sides of the unit D. The slats 10 and 10' are cut out so as to receive 115 the strip portion 16 and 22 and so that the abutting edges of the slats 10 will tightly engage against the contacting portions of the unit B or D. After the slats 10 have been placed on top of the unit D, then one of the units B may be placed 120

on top of the slats 10 and then another series of slats 10 placed on top of this unit B after which the next unit B is placed against the upper edges of the slats 10 and the remaining number of slats 10 placed on top of the last partition unit B placed in the crate A.

It will be noted as many partitions as may be desired may be placed in the crate A and that the slats 10 may be arranged so that the width thereof provides a spacing means which properly spaces the bottom and the partition units B in the crate A. After all of the units B and D are in position and the slats 10 have all been placed in proper relation between the corner members 13 and 14, it is desirable that the slats 10 be squeezed down tightly and then suitable rivets 25 may be passed through the corner members 13 and 14 so as to rigidly clamp the bottom unit D and the partition units B in place between the edges of the slats 10. In this manner the units B and D form a simple means of construction for the crate A and are cushioned between the slats so as to protect the same and hold the units virtually cushioned between the slats 10. The simplicity of this crate provides an economical means of forming a strong and durable bottle crate which may be used either for milk bottles or as a bottle carrier of any desirable nature.

In accordance with the patent statutes, we have described the principles of our bottle crate and the unitary nature of the bottom and partition units, however, the drawing and specification merely endeavor to point out a manner in which these may be made and connected together and the invention should be interpreted within the scope of the following claims:

We claim:

1. A bottle crate made up of a series of removable narrow slatted non-metallic members, metal reinforced corner members open at the top and extending over the corners of said members on the inside and outside thereof, and partition and bottom units held between said slatted members as a unit removably clamped by said slatted members.
2. A bottle crate including, a series of non-metallic slat-like members, means for holding said members together to form side walls with said members edge to edge, and an outer surface on said side walls partition and bottom units held extending partially over said outer surface and extending between said slatted members.
3. A bottle crate comprising, a series of rectangularly formed partition units having a strip-like outer portion, a series of right angularly disposed stay-rivets connecting the sides of said strip portion to provide a unit partition, and a series of narrow slat-like members clamping said rivets and adapted to space one or more of said partition units between the edges of said slat-like members to provide a divided bottle crate with individual bottle compartments.
4. A partition unit for a bottle crate in combination with a crate structure having the side walls made up of a series of slatted members, said unit partition including a strip-like member formed to provide a rectangular frame, a series of right angularly disposed stay-rivets extended between the sides of said frame, the slatted side members of said crate holding said partition unit therebetween, and means for securing said side members of said crate to hold the same firmly

clamped together with said partition unit between the edges of the side slats.

5. The combination, a series of slat-like members adapted to be superimposed edge to edge to provide side walls for a crate, partition units including a rectangular strip-like frame portion, stay-rivets extending right angularly to each other riveted to said frame portion, a bottom having a strip-like rectangular frame, stay-rivets extending in pairs in parallel relation between the sides of said frame to form bottom portions, and means for holding said partition units and said unitary bottom between said slats to cushion the same therebetween and in a manner to provide a bottle crate having individual bottle compartments and bottoms therefor.

6. A crate for bottles including, side walls made up of a series of slats, partition units including a series of crossed partition members, means for holding said partition members clamped between adjacent slats, and a strip edge secured to the extreme ends of said partition members.

7. A crate for bottles including, side walls made up of a series of slat members, partition units comprising a strip-like edge and connecting partition members extending between the sides thereof, said strip edge adapted to enclose between the opposite sides thereof portions of adjacent slat members, and means for holding said partition members clamped between said slats.

8. A crate for bottles including, side walls made up of a series of slats, partition units made up of a frame member and partition members extending between the sides of said frame, and grooves in some of said slats on the outside thereof to accommodate said frame so that strain exerted against said partition members exerts an inward pressure against the outside of the frame.

9. A bottle crate including, slats placed edge to edge to form side and end walls, corner members for holding said slats in proper relationship, and partition units comprising rectangular frame means having strip-like side walls, partition members connecting opposed sides of said frame means, said unit being sandwiched between the edges of adjacent slats, the inside of the frame side walls bearing against the outside of the slats.

10. A crate comprising side walls formed of slats placed edge to edge, means for holding said slats in proper relationship, and partition units comprising a strip-like frame adapted to bear against the outside of some of said slats, and partition members connecting opposed sides of said frame.

11. A crate comprising side walls, a strip-like frame adapted to extend around the outside of said side walls, and partition members connecting opposed sides of said frame extending through said side walls.

12. A bottle crate having partitions, each including a narrow strip-like member formed to provide a rectangular frame, a series of stay-rivets of smaller diameter than the width of said strip-like member extending between the sides of the frame, the crate including a series of wall members forming the crate walls, these wall members extending within said strip-like members for holding each frame as a unit between the wall members of the bottle crate to form partitions and a bottom for bottles held in said crate.
